UNITED STATES PATENT OFFICE.

MINOR HARVEY, OF PHILADELPHIA, PENNSYLVANIA, ASSIGNOR TO MORSE, WILLIAMS AND COMPANY, A CORPORATION OF PENNSYLVANIA.

ELECTRICALLY-DRIVEN ROLLING-MILL.

SPECIFICATION forming part of Letters Patent No. 699,950, dated May 13, 1902.

Application filed January 10, 1901. Serial No. 42,707. (No model.)

To all whom it may concern:

Be it known that I, MINOR HARVEY, of the city and county of Philadelphia and State of Pennsylvania, have invented an Improvement 5 in Electrically-Driven Rolling-Mills, of which the following is a specification.

My invention has reference to electrically-driven rolling-mills; and it consists of certain improvements, all of which are fully set forth 10 in the following specification and shown in the accompanying drawings, which form a part thereof.

The object of my invention is to provide driving means for rolling-mills which shall 15 cause the rolls to operate smoothly, accurately, and with great power, while at the same time taking up a minimum of floor-space.

My invention comprehends certain improvements whereby the power-shaft for operating the rolls shall be carried in bearings 20 on the top of the housings and connected with one or both rolls by power-transmitting connections, preferably in the form of shafts and gearing.

25 In carrying out my invention I provide the respective rolls with elongated shafts extending through the bearings in the housings in opposite directions, and these I connect by worm and worm-wheel gearing with two vertical shafts having their upper ends geared together with a transverse driving-shaft which may be driven by an electric motor or otherwise. This transverse shaft is supported 30 in bearings above the housings of the rolls and arranged, preferably, in a diagonal direction relatively to the axis of the rolls, so that the worms and their vertical shafts may be arranged, respectively, upon opposite sides of their worm-wheels to cause the rolls to rotate in opposite directions.

My invention also embodies many details of construction, all of which will be better understood by reference to the drawings, in which—

45 Figure 1 is an elevation of a rolling-mill, with part in section, embodying my improvements. Fig. 2 is a side elevation of same. Fig. 3 is a plan view of same with part of the gearing removed, and Fig. 4 is a plan view showing a 50 modified form of the gearing adapted to my invention.

A A are the housings of the rolling-mill.

B B' are the two rolls, and b b' are the extended shafts of the respective rolls. These rolls are journaled in suitable adjustable bearings, (not shown,) as is customary in rolling-mills of this character. 55

The type of rolling-mill shown in this application is that adopted by the United States Government for mint purposes; but the only 60 portions thereof which are of special interest to this application are the means of applying power for operating the rolls and to which the claims are specially directed. The ends of the shafts b b' are provided with worm-wheels C, 65 as shown in Fig. 3. Meshing with these worm-wheels C are the worms D, secured upon vertical shafts d; but I prefer to arrange the said worms and their shafts upon opposite sides of the respective worm-wheels, so as to cause 70 them and their rolls to rotate in opposite directions.

E represents casings inclosing the gears C D and to provide a receptacle to contain oil to secure perfect lubrication of the gears. 75 The casings have horizontal bearings c for the horizontal shafts b b' of the rolls and vertical bearings R F to receive and guide the vertical worm-shafts d. The upper bearing R is secured to the top of the casing E and also 80 carries a stuffing-box e, through which the shaft d extends. The lower bearing F is formed on a cap-plate or head E', bolted to the lower part of the casing and provided with ball-bearings f, upon which the shaft d is 85 stepped. These ball-bearings f may be adjusted vertically by an adjusting-screw G, if so desired. Interposed between the upper bearing R and the worm D is a ball thrust-bearing i, the upper plate of which is ad- 90 justed by the wedge J, having an upper-inclined edge working against a fixed cam I on the upper bearing. This wedge J is adjustable laterally by the screws K K. By means of this adjusting-wedge J and the adjusting-screw G the vertical shaft d may be held against loose play and the proper position of the worm D relatively to the worm-wheel C definitely secured. This is important in a construction such as shown, wherein the roots 95 of the spirals of the worm are on a curve corresponding with the maximum curvature of 100

the worm-wheel C, because to secure the best results the worm should be adjusted vertically to suit any vertical adjustment of the rolls B B' in setting up the machine when adjusting the worm to the worm-wheel or when adjusting the worm to compensate for wear in the bearings.

- 5 The casings E are made in segments, so as to be removed to expose the gears or readily 10 applied in setting up the rolls. The gear-bearing and casing structures on each side of the housings is the same, one set being applied to the shaft b of the upper roll B and the other set to the shaft b' of the lower 15 roll B'. It thus follows that they are located at different elevations, corresponding to the distance between the axis of the rolls. It will also be seen that the two shafts d are also of different lengths for the same reason.
- 20 The upper ends of the long shafts d are received in sockets in the short shafts T, journaled in the bearings L, which latter are connected in any suitable manner in fixed relation to the top of the housings A. As shown, 25 these bearings L are secured to the base-frame H' of the electric motor H, which in turn is secured to the top of the housings A by standards h. The shaft N of the electric motor H is horizontal and geared to the short 30 shafts T by bevel or miter gears M, inclosed, if desired, in cases m. The connection between the shafts d and T is such that while permitting of vertical adjustment they positively rotate together. The most convenient 35 way of securing this is to employ a heavy key or to make the upper end of the shafts d square and fitted to a square socket in shafts T, said structure being well-known mechanical equivalents.
- 40 By examining Fig. 3 it will be observed that the shafts d are in diagonal alignment relatively to the axis of the rolls, and for this reason the motor H is set diagonally, so as to make its shaft N correspond to the diagonal 45 alignment of the shafts d, thereby securing the most simple and direct power-transmission and even distribution of the live load above the rolling-mill proper. This enables a small base to be used on the mill, small vibration produced, and a minimum strength of anchoring devices necessary. This diagonal arrangement is more especially applicable to use with slow-speed motors; but in cases where high-speed motors are used the miter- 50 gears M may be replaced by worm and worm-wheel gearing, as at M' in Fig. 4, in which case the motor-shaft N may be arranged parallel to the axis of the rolls and have its weight centrally distributed above the housings.
- 55 While I prefer to rotate both rolls independently from the power-shaft by separate sets of shafts and gearing, it is evident that I may employ only a single set of power-transmitting connections to one of the rolls and 60 allow the two rolls to be directly geared together in the common and well-known manner.

I have shown an electric motor as the immediate source of power for operating the power-shaft N in its bearings n on the base H'; but 70 I do not limit my invention to any particular power, as the shaft N may be driven in any manner desired.

While I prefer the construction illustrated as being well adapted to the purpose of my 75 invention, I do not limit myself to the details thereof, as they may be modified in various ways without departing from the spirit of the invention.

Having now described my invention, what 80 I claim as new, and desire to secure by Letters Patent, is—

1. The combination of the two rolls of a rolling-mill, with two vertical shafts and connecting worm and worm-wheel gearing arranged upon opposite ends of the two rolls for independently and mechanically rotating the respective rolls, a transverse power-shaft carried in suitable bearings on the top of the housings of the rolling-mill, and independent 85 connecting-gearing between the ends of the power-shaft and the upper ends of the two vertical shafts.

2. The combination of the two rolls of a rolling-mill, with two vertical shafts and connecting worm and worm-wheel gearing arranged upon opposite ends of the two rolls for independently and mechanically rotating the respective rolls, a horizontal transverse and diagonally-arranged power-shaft carried in 90 suitable bearings on the top of the housings of the rolling-mill, and independent connecting-gearing between the ends of the power-shaft and the upper ends of the two vertical shafts.

3. In a rolling-mill, the combination of the housings and horizontal rolls journaled therein one of which has its end projecting beyond the end of the other roll, a motor for operating the rolls secured on top of the housings 100 and above the rolls and provided with a transverse power-shaft, a worm-wheel secured to the projecting end of the roll and extending beyond the line of the shorter end of the other roll, an upright shaft extending from the level 105 of the rolls to the power-shaft, gearing between the power-shaft and upright shaft, and a worm on the upright shaft gearing with the worm-wheel of the rolls.

4. In a rolling-mill, the combination of the 110 housings and horizontal rolls journaled therein one of which has its end projecting beyond the end of the other roll, a motor for operating the rolls secured on top of the housings and above the rolls and provided with a transverse power-shaft, a worm-wheel secured to the projecting end of the roll and extending beyond the line of the shorter end of the other roll, an upright shaft extending from the level 115 of the rolls to the power-shaft, gearing between the power-shaft and upright shaft, a worm on the upright shaft gearing with the worm-wheel 120 of the rolls, and a casing inclosing the worm and worm-wheel gearing secured to the hous- 125

ing and provided with a bearing for the upright shaft.

5. In a rolling-mill, the combination of the housings and the two rolls, with a motor for rotating the rolls arranged immediately above and supported by the housing, and two sets of power-transmitting connections between the motor and the opposite ends of the respective rolls for rotating them in opposite directions.

6. In a rolling-mill, the combination of the housings, the two rolls having their operating-shafts extended through the housings in opposite directions, worm-wheels secured upon said extended roll-shafts, worms meshing with opposite sides of said respective worm-wheels upon the upright shafts for operating the worms, and a diagonally-arranged power-shaft carried in bearings upon the upper part of the housings and having its ends mechanically connected with the upper ends of the upright shafts.

7. In a rolling-mill, the combination of the housings the two rolls having their operating-shafts extended through the housings in opposite directions, worm-wheels secured upon 25 said extended roll-shafts, worms meshing with opposite sides of said respective worm-wheels upon the upright shafts for operating the worms, a diagonally - arranged power - shaft carried in bearings upon the upper part of the housings 30 and having its ends mechanically connected with the upper ends of the upright shafts in-closing casings surrounding the worms and worm-wheels secured to the housings at different elevations and provided with bearings 35 for the upright shafts.

In testimony of which invention I have hereunto set my hand.

MINOR HARVEY.
